H. G. BALTHASAR,

WHISTLE.

APPLICATION FILED MAY 12, 1919.

1,331,975.

Patented Feb. 24, 1920.

UNITED STATES PATENT OFFICE.

HARRY G. BALTHASAR, OF ST. LOUIS, MISSOURI, ASSIGNOR TO COMBINATION AUTO LOCK COMPANY, OF ST. LOUIS, MISSOURI, A CORPORATION OF MISSOURI.

WHISTLE.

1,331,975.

Specification of Letters Patent. Patented Feb. 24, 1920.

Application filed May 12, 1919. Serial No. 296,307.

To all whom it may concern:

Be it known that I, HARRY G. BALTHASAR, a citizen of the United States, residing at the city of St. Louis, in the State of Missouri, have invented certain new and useful improvements in Whistles, of which the following is a specification.

This invention relates to whistles or signaling devices operated by fluids under compression, and is particularly adapted for use in connection with a cylinder of an internal combustion or explosive engine, such, for instance, as an automobile engine, a motorcycle engine, or the like.

It has for an object to provide a device of the character described that is of simple construction and that may be attached readily in operative position in direct connection with the cylinder, so that the fluid under compression in the cylinder may be used for sounding the whistle.

Another object is to provide a device of the character described having a valve of simple construction adapted for controlling the passage of fluid under compression thereto from the engine cylinder, so that the pitch or intensity of the alarm may be regulated effectively and with facility.

Other objects, and the advantages of the device of this invention, are hereinafter set forth.

In the accompanying drawings forming part of this specification, in which like numbers of reference denote like parts wherever they occur,

Figure 1 is a side elevation of the casing containing a plural cylinder explosive or internal combustion engine, such as the engines used for automobiles, with the device of this invention operatively mounted on a priming cup opening in connection with one of the cylinders of the engine;

Fig. 2 is an enlarged view of the device of this invention shown in Fig. 1 and removed from the engine cylinder;

Fig. 3 is a sectional view taken on the line 3-3 in Fig. 2, showing the valve in closed position; and

Fig. 4 is a fragmentary view of the valve-bearing portion of Fig. 3 and parts adjacent to the valve, showing the valve in open position.

Whistle body 1 is a hollow member adapted as a sound chamber, and may be of any suitable material, such, for instance, as brass

or aluminum, and may be substantially elliptical in general outline, as best seen in Fig. 2, and is provided with a lateral opening 2, across which opening air or other fluid, expelled under compression into the whistle body, is projected, as hereinafter described, for the purpose of sounding the alarm with a resonant harmonious sound of a pleasing yet warning intonation. The base end of whistle body 1 is provided with an opening 3 adapted to communicate with the interior of perforated valve stem casing 4 borne by said base end, the end of said casing adjacent the base of whistle body 1 bearing nut-shaped flange 5, and the other end of said casing being externally screw-threaded, as best seen in Figs. 3 and 4. The perforation of casing 3 is provided with an enlarged chamber 6 intermediate the base of whistle body 1 and the screw-threaded end 70 of casing 3, there being an oblique slot or passage 7 through which fluid under pressure may be expelled from chamber 6 into whistle body 1 and across opening 2 of said whistle body, as hereinafter described. 80 Valve seat 8, formed at the screw-threaded end of casing 4, is adapted to coact with the seating face 9 of valve 10, said seat and said face being preferably ground, to provide a fluid-tight joint when said valve is seated on said seat in closing position shown in Fig. 4, slot 11 in the head of valve 10 being provided for the well-known purpose of receiving a tool for conveniently grinding the said valve face and the said seat together to a perfect fit.

Valve-stem 12 is adapted to be mounted in the perforation of casing 4, one end of said stem bearing valve 10, and the other end of said stem extending through opening 95 3 in the base of whistle body 1 and into the hollow portion of said whistle body, as best seen in Figs. 2 and 3, the diameter of said valve-stem 12 being such that there is a clearance space provided in the perforation 100 of casing 4, when stem 12 is mounted therein, so that when valve 10 is in unseated or open position there is a communicating passage outwardly from enlarged chamber 6 through the seat-bearing end of casing 4.

To support valve 10 normally in seated or closed position, spiral spring 13 is provided, said spring being mounted on the portion of valve-stem 12 within the hollow portion of whistle body 1, one end of said spring being 105 110

- attached to the inner end of said valve-stem 12 in any suitable manner, such, for instance, as by means of transverse perforation 14 formed in said valve-stem 12, the 5 other end of said spring 13 being adapted to bear against the inner wall of whistle body 1 adjacent opening 3, so that valve 12 is normally held in closed or seated position under the spring tension of the spring 13.
- 10 Casing 4 is transversely perforated through flange 5 by means of perforation 15, said perforation communicating with enlarged chamber 6, and one end of bent lever or key 16 is mounted in said perforation 15, and is adapted 15 to extend therethrough, there being a notch or cut-out portion 17 formed in said lever within said enlarged chamber 6, and adapted to coöperate with a similar notch or cut-out portion formed on valve-stem 12 20 within said enlarged chamber, so that in a position such as that shown in Fig. 3 the said notched portion of said lever and said valve-stem will coöperate to permit the spring 13 to hold valve 10 in seated or closed 25 position, but when the lever 16 is rotated to a position wherein the rounded or uncut or unnotched portion thereof bears against a shoulder formed by the notch 18 in valve stem 4, as shown in Fig. 4, valve 12 will be 30 in open or unseated position until the said lever 16 is further revolved, and the flat face of notch 17 of lever 16 passes beyond the said shoulder formed by notch 18, whereupon the tension of spring 13 will act to 35 draw valve 12 back to seated or closed position. The other end of lever 16 may be bent, as best seen in Fig. 2, and may terminate in an eye 19 adapted for attaching thereto one end of lever-operating cord 20 40 or the like, said cord having its other end within convenient reach of the driver of the automobile or the operator of the machine or apparatus with which the device of this invention is equipped.
- 45 Reducing nipple 21 may be provided, having its enlarged portion internally screw-threaded and adapted to engage the screw-threaded end of casing 4 so that said enlarged end of said nipple 21 may be screwed 50 home into position on said case, there being a well or clearance at the bottom of the enlarged bore of said nipple, when same is screwed in place, between the seat-bearing end of said casing and the bottom of said 55 enlarged bore, to provide a valve chamber sufficient for valve 10 to be moved therein from and to seated or closed position, as best seen in Figs. 3 and 4.
- The reduced end of said nipple 21 is externally screw-threaded, and is adapted to 60 be screwed into a correspondingly-threaded priming-cup opening of a cylinder of engine 22, after a priming cup, such as those shown at 23 in Fig. 1, has been removed, for the 65 purpose of mounting the device of this in-

vention in operative association with a cylinder of engine 22, substantially as shown in Fig. 1, so that when valve 12 is moved to open position, as shown in Fig. 4, by appropriately manipulating valve lever or key 16, 70 air or the like, under compression at the intake stroke of the engine, will pass from the cylinder, in connection with which cylinder the device of this invention is operatively mounted, through nipple 21 and through the 75 passage in casing 4, communicated with when the said valve 12 is in open position, to enlarged chamber 6 and thence through slot 7, thus being projected into the hollow portion of whistle body 1 and across lateral 80 opening 2 to sound the alarm, and, when valve 12 is moved to closed position (Fig. 3), communication through the said passage will be sealed so that air or fluid under pressure in said cylinder will cease to be expelled 85 from the cylinder through the said passage, and the alarm will cease to sound.

A great advantage of the device of this invention is that the alarm is at all times under the complete control of the operator, 90 and, the device being in communication with the cylinder of the engine, there is no tendency toward clogging the parts or passages of the device with dirt or the like, as is the case with whistle alarms operated by the 95 exhaust of internal combustion engines.

For convenience in manufacturing, whistle body 1 is formed with opening 24 at the top thereof, which opening is closed by means of double-flanged cap 25, one flange 26 being 100 adapted to engage the outer wall of whistle body 1 adjacent opening 24, and the other flange 27 being adapted to be crimped against the inner wall of said whistle body 1 adjacent said opening 24. Cap 25 is preferably made of thinner material than the remaining portion of whistle body 1, so that said cap will tend to vibrate more rapidly than surrounding portions of the whistle body when fluid under pressure is projected 105 into the whistle body.

It is, of course, understood that in the case of an engine having a plurality of cylinders, more than one cylinder may be equipped with a device of this invention. 115

Having thus described this invention, I hereby reserve the benefit of all changes in form, arrangement, order, or use of parts, as it is evident that many minor changes may be made therein without departing from the 120 spirit of this invention or the scope of the following claim.

I claim:

A whistle alarm for operative association with internal combustion engines, comprising 125 a one-piece body-member, said body-member carrying a resiliently-mounted valve, said valve seating against the lower end of the body-member, a spring surrounding said valve stem, held at one end in fixed 130

position and at its other end by abutting against the inner wall of the body member, said valve stem having a transverse slot for engagement with the valve-actuating means, 5 said valve-actuating means comprising a lever transversely mounted through said body-member and engaging the slot in said valve stem, whereby said valve is caused to

unseat, thereby operating the whistle, and a union attached to said one-piece body-member for connecting said member with an engine. 10

In testimony whereof I hereunto affix my signature.

HARRY G. BALTHASAR.
